UNITED STATES PATENT OFFICE.

GEORGE HOEPNER, OF CHICAGO, ILLINOIS.

SEWING-MACHINE.

1,259,740.

Specification of Letters Patent. Patented Mar. 19, 1918.

Application filed October 27, 1916. Serial No. 128,104.

To all whom it may concern:

Be it known that I, GEORGE HOEPNER, a citizen of the United States, residing at Chicago, county of Cook, State of Illinois, have invented a certain new and useful Improvement in Sewing-Machines, and declare the following to be a full, clear, and exact description of the same, such as will enable others skilled in the art to which it pertains to make and use the same, reference being had to the accompanying drawings, which form a part of this specification.

Viewed in one of its aspects my invention may be said to have for its object to produce a simple, powerful and reliable machine for rapidly and effectively sewing up the mouths of filled fabric bags or sacks.

One of the difficulties experienced in sewing up the mouths of large filled sacks or bags arises from the considerable bulk and weight of each piece of work which causes its manipulation to be far from easy and simple. Viewed in one of its aspects my invention may be said to have for its object a simple means of supporting and controlling a bulky piece of work such as a heavy filled bag, whereby its manipulation is made easy and convenient and it may be shifted back and forth with the expenditure of practically no effort.

The various features of novelty whereby my invention is characterized will herein-after be pointed out with particularity in the claims; but, for a full understanding of my invention and of its objects and advantages, reference may be had to the following detailed description taken in connection with the accompanying drawings, wherein:

Figure 1 is a front elevation of a machine arranged in accordance with a preferred form of my invention;

Fig. 2 is a side elevation, looking toward the left from the right hand side of Fig. 1;

Fig. 3 is a section on an enlarged scale taken approximately on line 3-3 of Fig. 1; and

Fig. 4 is a view taken approximately on line 4-4 of Fig. 3.

Referring to the drawing, 1 represents a suitable base from which rises a post or standard, 2. On the upper end of the post or standard is supported a sewing machine head, 3, so located that it will operate upon the upper end of a bag positioned beside the post. The sewing machine head may conveniently be a unit carried by a bracket, 4,

which is attached to the post by a suitable clamp, 5. Beside the post is a vertical shaft, 6, which is revolvably supported, conveniently by means of a suitable bearing at the upper end in the bracket 4 and a suitable bearing in a bracket, 7, attached to the post adjacent to the lower end of the shaft. On the shaft 6 is a suitable bracket device, 8, adjustable lengthwise of the shaft but held against rotation thereon. This may conveniently be accomplished by providing the shaft with a flattened portion as indicated at 9 and providing the bracket with a set screw, 10, engaging with the flattened portion and thus performing the double function of holding the bracket, 8, in any desired position lengthwise of the shaft and against rotation on the shaft. The bracket 8 carries a suitable horizontal platform or table, 11, which is preferably segmental in form and has at the inner edge an upwardly projecting flange, 12. An upright member, 13, is carried by the bracket 8 just in rear of the table or platform, 11, and on the upper end of the member 13 is a curved shoe or guard, 14, of approximately the same contour as the flange 12 and lying almost immediately above the same. The member 14 may be adjusted on the upright, 13, by loosening a holding screw, 15. The upright 13 may be adjusted vertically relatively to the bracket 8 upon loosening a holding screw, 16; this adjustment being desirable to permit the lower end of the member 13 to remain at a predetermined relation to the base of the machine, regardless of the elevation of the supporting platform or table.

It will be seen that the work supporting table swings about the axis of the shaft 6, the angle of its swinging movement being indicated in Fig. 3 wherein the table is shown in full lines in its work-receiving position with the bracket, 8, engaging with the main supporting post, while the other limit of the movement of the table is illustrated in dotted lines which shows the position of the table after the work has been carried past the sewing machine head.

I prefer so to construct the apparatus that the table will always return to its work-receiving position when free to do so so that when empty it will always be ready to receive a bag and need not be adjusted for this purpose. This may conveniently be accomplished by providing a weight, 17, attached to one end of a cable, 18, which passes

over a pulley, 19, on the main supporting post and is attached to the end of a projecting arm or finger, 20, attached to the shaft 6. The parts are so proportioned that the 5 weight 17 will always turn the shaft in the direction to bring the table into its work-receiving position, when free to do so. While it is desirable to have the table return automatically to a normal position, 10 it is at the same time necessary to provide means for carrying the work forward during the sewing operation, in order to relieve the sewing machine feeding devices from the strain which would be imposed 15 on them if they were required to pull a heavy filled bag forwardly as the sewing progresses. To this end I have provided a power device in which is stored sufficient power to swing the table against the 20 resistance of the weight 17 when a forward movement of the work is desired and which again becomes inoperative or ineffective when the work is done. This is conveniently accomplished by connecting a 25 spring to the shaft 6 in such a way that when the machine is started the spring will be placed under tension, while upon stopping the machine the tension will be relieved. In the arrangement shown, I have 30 attached to the lower end of the shaft 6 a flexible member, 21, which partially surrounds the shaft; the free end of the member 21 being connected to one end of a spring, 22, which is in turn connected to one arm 35 of a bell crank lever, 23. The other arm of the bell crank lever is provided with an anti-friction roller, 24, which is engaged by one end of a lever, 25, whose other end overlies an operating treadle, 26. When the operator 40 presses his foot on the treadle the levers 25 and 23 are actuated in a direction to place the spring 22 under tension sufficient to overcome the resistance to forward movement of the loaded table. It is desirable 45 that the table be held in its work-receiving position in such a way that it will remain stationary while the work is being placed on it and to this end I have provided a catch which is released when the 50 treadle is depressed. The catch may consist conveniently of a bar, 27, pivotally supported between its ends as at 28 on the base of the machine; the bar having on one end a hook, 29, adapted to engage with the 55 lower end of the upright member 13, and having its other end overlying the treadle 26 in such a position that when the treadle is depressed the hook 29 is carried down below the lower end of the upright 13 and releases the table. 60

The operation of the treadle to release the table and store up power in the actuating spring also starts the sewing machine through an arrangement which I shall now 65 describe. On the main supporting post,

above the sewing machine, is supported a motor, 30, from which extends a belt, 31, passing over a pulley, 32, running loosely on a stationary horizontal shaft, 33. It will be seen that just beside the pulley 32 is a 70 second pulley, 34, also loosely mounted on the shaft 33. On the shaft 33 at one side of the pulleys is fixed a block, 35, having a V-shaped depression in one end; and between the block 35 and the pulley 32 is a 75 rotatable block, 36, having a V-shaped projection entering the depression in the block 35. It will be seen that by turning the block 36, its wedge shaped end riding up one of the walls of the V-shaped depression in the stationary block, causes the block 36 to move lengthwise of the shaft and to force the pulley 32 toward the pulley 34. When the two pulleys are pressed together, the friction between them causes 80 them to turn in unison with each other. The block 36 is provided with a radially extending arm, 40, which is connected by a rod, 41, to the rear end of the treadle 26, the parts being so proportioned that when 85 the treadle is depressed the block 36 is rotated and causes the two pulleys 32 and 34 to be clutched together. The sewing machine is driven by a belt, 42, passing from the pulley 34 to a pulley, 43, on the main 90 shaft of the sewing machine. 95

The sewing machine head is in the form of an inverted U in the lower end of one of the arms of which is supported a horizontal reciprocable needle bar, 47, and a presser foot bar, 48, arranged parallel with each other. In the arrangement illustrated, the machine is a double thread machine, there being two threads, 85 and 92, respectively, extending from spools supported in any 100 suitable way, preferably above the post 2. 105

It will now be seen that I have produced a simple, compact and powerful machine by which heavy bags may be easily and conveniently closed, which will permit a double 110 bag consisting of an inner member and an outer member to be passed through the machine twice so as to sew the two members separately, without disturbing the position of the bag on the table or support; the bag 115 being simply swung back after the inner member has been sewed and being passed again through the machine to sew the outer member. In the same way, if the thread breaks when the seam is partly made, it is 120 unnecessary to change the position of the bag on its support, the bag and its support being swung back to permit the sewing to start over again at the desired point. 125

While I have illustrated and described with particularity only a single preferred form of my invention, I do not desire to be limited to the exact structural details thus illustrated and described; but intend to cover all forms and arrangements which 130

come within the terms employed in the definitions of my invention constituting the appended claims.

I claim:

- 5 1. In combination, a sewing machine, a work support movable back and forth past the sewing machine, means tending constantly to bring said support to one limit of its movement, and means for simultaneously 65 setting the sewing machine in operation and causing the support to travel toward the other limit of its movement.
- 10 2. In combination, a sewing machine, a work support movable back and forth past 70 said sewing machine, means tending constantly to move said support in one direction, a device adapted to move said support in the other direction in opposition to the aforesaid means, and means for controlling 75 the action of said device on said support.
- 15 3. In combination, a sewing machine, a work support movable back and forth past said sewing machine, means tending constantly to move said support in one direction, 80 a device adapted to move said support in the other direction in opposition to the aforesaid means, and means for simultaneously setting the sewing machine and said device in operation and for simultaneously 85 stopping the sewing machine and rendering 90 said device inoperative.
- 20 4. In combination, a sewing machine, a work support movable back and forth past said sewing machine, means tending constantly to move said support in one direction, 95 a power device connected to the support for moving it in the opposite direction, and means for simultaneously setting the sewing machine in operation and storing power in 100 said power device.
- 25 5. In combination, a sewing machine, a work support movable back and forth past said sewing machine, means tending constantly to move said support to one limit of its movement, a catch for holding said support at the latter limit, a power device connected to the support for moving it toward the other limit of its movement, and means for simultaneously releasing said catch and 105 storing power in said power device.
- 30 6. In combination, a sewing machine, a work support mounted so as to be capable of moving back and forth past the machine, means tending constantly to move the support in one direction, a spring adapted to move the support in the opposite direction, and means for intermittently storing sufficient power in the spring to cause it to move 110 the said support.
- 35 7. In combination, a post, a sewing machine mounted on the upper end of the post,

a horizontal work support mounted on said post below the machine so as to be capable of swinging back and forth beneath the machine, means tending constantly to move said 65 support in one direction, and means for simultaneously setting the sewing machine in operation and causing the support to move in the other direction.

8. In combination, a post, a sewing machine at the upper end of the post, a vertical shaft revolubly supported at one side of the post, a horizontal bag support mounted on the said shaft and adjustable lengthwise of the latter, a weight acting on the shaft 75 and adapted to turn it in one direction, a spring connected to the shaft and adapted to turn it in the other direction when placed under sufficient tension, and means for simultaneously starting the sewing machine and 80 placing said spring under tension.

9. In combination, a post, a sewing machine at the upper end of the post, a vertical shaft revolubly supported at one side of the post, a horizontal bag support mounted on 85 the said shaft and adjustable lengthwise of the latter, means tending constantly to turn said shaft in one direction, and means for simultaneously setting the sewing machine in operation and causing the shaft to turn 90 in the opposite direction.

10. In combination, a sewing machine, a work support mounted so as to be capable of swinging back and forth past the sewing machine, means independent of the sewing 95 machine for moving said support in one direction, additional means for moving said support in the opposite direction, and a common controller for said sewing machine and said means.

11. In combination, a sewing machine, a work support movable back and forth past the sewing machine, means for moving said support in both directions, a catch for holding said support at one limit of its movement; and a common controller for said sewing machine, said means and said catch.

12. In combination, a vertical supporting post, a sewing machine in the form of an inverted U attached to the upper end of 110 the post and arranged at one side thereof, an oscillatory vertical shaft arranged beside said post, a work-supporting table fixed to said shaft at a point below said sewing machine, means for oscillating said shaft in 115 both directions so as to carry the table back and forth, and a common controller for said sewing machine and said means.

In testimony whereof, I sign this specification.

GEORGE HOEPNER.
